UNITED STATES PATENT OFFICE

2,153,865

TUNING APPARATUS FOR RADIO RECEIVERS

Adolph E. Gersch, Chicago, Ill., assignor to
Stewart-Warner Corporation, Chicago, Ill., a
corporation of Virginia

Application August 21, 1937, Serial No. 160,238

16 Claims. (Cl. 250—40)

This invention relates to new and improved tuning apparatus for radio receivers and more particularly to means whereby a radio receiving set may be automatically tuned to a desired frequency by a selective manual control.

The present-day radio receiver comprises as its tuning element a multiple unit variable condenser which varies the capacity in a plurality of circuits simultaneously by means of the rotation of a single shaft. The usual tuning control for variation of frequency comprises a rotatable knob which serves either directly or through a speed reduction means to rotate the condenser shaft. A calibrated dial is driven from the condenser shaft so that the user may observe the tuning operation and locate the desired station frequency.

While some such dials carry the radio station designations to assist in tuning, this is generally impractical due to the large number of such stations and due to the fact that such a dial becomes obsolete with changes of frequencies or of station call letter assignments. When the dial is merely calibrated in frequencies, it is necessary for the user to know the operating frequency of the desired station and to observe the dial carefully and to adjust it slowly when near the desired frequency. The large number of stations on the air renders it difficult to memorize the frequencies of all stations which it may be desired to receive from time to time.

It is an object of the present invention to provide tuning apparatus for radio receivers whereby the apparatus may be easily and rapidly tuned to a desired station frequency.

It is a further object to provide such tuning apparatus provided with a plurality of manually operable controls, each of which serves to tune the apparatus to an indicated station.

It is also an object to provide such apparatus wherein the automatic controls may each be easily and quickly adjusted to serve to tune the set to a desired frequency.

It is an additional object to provide a construction in which this adjustment may be carried out by unskilled persons without knowledge of the details of the mechanism.

It is a further object to provide such an apparatus for the control of a tuning device operable through a limited arc, the apparatus automatically selecting the direction of rotation from any initial point to reach any other selected point within the arc of movement.

It is also an object to provide apparatus of this character which may be readily discon-

nected to permit the usual continuous manual adjustment of the tuning device.

It is an additional object to provide apparatus of this type which will automatically silence the radio receiver during the automatic adjustment of the tuning device.

It is a further object to provide such apparatus which automatically cuts into and out of circuit an automatic frequency control circuit at predetermined portions of the cycle of operation.

It is also an object to provide an apparatus which will automatically control indicating means to show to the user whether the apparatus is adjusted for automatic or continuous manual operation.

It is an additional object to provide an apparatus of this character, in which the resumption of manual tuning by the user automatically adjusts the mechanism for manual tuning.

Other and further objects will appear as the description proceeds.

I have shown certain preferred embodiments of my invention in the accompanying drawings, in which—

Figure 1 is a plan view of the control apparatus in position for manual operation, with parts broken away for the sake of clearness;

Figure 2 is a front view of the apparatus of Figure 1, with the dial or indicating mechanism associated therewith;

Figure 3 is a fragmentary view of a portion of the left end of Figure 1;

Figure 4 is a fragmentary view showing a control cam and associated clamping cup assembled on the shaft;

Figure 5 is a fragmentary section of the construction of Figure 4;

Figure 6 is an end elevation taken from the right end of Figure 1;

Figure 7 is a sectional elevation taken on the line 7—7 of Figure 1;

Figure 8 is a schematic diagram showing the electrical connections and switches actuated during the operation of the mechanism, with the clutch in automatic control position;

Figure 8a is a schematic diagram showing the cam and cam bar actuating the switch cam of Figure 8;

Figure 9 is a fragmentary view, on an enlarged scale and partly in section, showing the cam disc clamping mechanism;

Figure 10 is a fragmentary view of the clamping mechanism, as seen from the right of Figure 9;

Figure 11 is a cross section taken on the line 11—11 of Figure 9;

Figure 12 is an exploded perspective view of the parts of the clamping mechanism; and

5 Figure 13 is a fragmentary section showing the friction brake mechanism.

Referring first to Figures 1, 2, 6 and 7, the mechanism is mounted in a sheet metal frame or housing having a U-shaped front member 11 and a flat rear closure member 12. As shown in Figure 2, this supporting structure 11 and 12 is mounted on a radio receiver chassis 13 by means of the brackets 14. The chassis 13 carries the dial 16 and indicator 17 by means of standard 15. This indicator 17 is driven by means of cable 18 passing over pulleys 19 and 20 and driven by the pulley 21, which is driven by means of the gear 22 from the automatic drive mechanism. The gear 22 is driven by gear 101 which is secured to the shaft 102 also carrying the gear 103. The gear 103 meshes with the crown gear 104 which is carried by the end of the main driven shaft 23. The details of this dial and indicating construction form no 20 part of the present invention and need not be described in further detail.

The automatic control mechanism includes the shaft 23 which extends longitudinally of the housing member 11 and is rotatably carried by the brackets 37 and 38 secured to the housing. As shown in Figure 3, this shaft 23 is provided with the longitudinally extending keyway 24. The stop disc 25 is keyed to the left end of the shaft, and this disc 25 carries the stop lug 26 which engages the stops 27 and 28 at either end of an 35 arc of rotation of 180°. Stops 27 and 28 are formed by the upper edges of inturned lugs which are bent in on the bracket member 37.

The shaft 23 supports a plurality of control 40 cam discs 31 which are rotatably carried by the shaft. Between each adjacent pair of control cams 31 are located a pair of clamping cups 32 which are oppositely faced so that the flat flange 33 of each cup engages a cam disc 31. This is best shown in Figure 5. The clamping cups 32 are all keyed to the shaft 23 in such manner that they may freely slide axially of the shaft, but are constrained to rotate with the shaft. A locating disc 34 is secured to the shaft 23 adjacent 45 the left face of the bracket 37 by set screw 35, as shown in Figure 1.

Adjacent the inner face of the bracket 38 the locking cup 30 is keyed to the shaft 23, the right-hand face of the cup having a plurality of cam 50 means 36 formed thereon. The cup 39 is rotatably carried on the shaft 23 adjacent the cup 35 and is provided with cam faces 40 coacting with the cams 36 on the cup 35. The cup 39 serves as a bearing for the shaft 23 and itself 55 fits in a circular opening 105 in the supporting bracket 38. Outside the bracket 38, the cup 39 has the gear 106 secured to it, a bearing washer 107 being between the gear 106 and the outer face of the bracket 38. The gear 106 has the struck up 60 lug 108 on its outer face. The spring 109 is held against the outer face of the gear 106 by the thrust plate 110 which is keyed to shaft 23 to rotate therewith. The thrust plate 110 is held against longitudinal movement along the shaft 65 23 to the right by the pin 111 which passes through the shaft. The spring 109 has a raised portion 112 adapted to latch over the lug 108 on the gear 106 in one position of the parts, as will be explained in detail in connection with the 70 operation of the apparatus.

As shown in Figure 7, the frame, formed of members 11 and 12, carries a plurality of push buttons 41, each of which is secured to the front end of a station-selecting slide 42. The buttons 41 are in two rows in order to reduce the required 5 linear extent of the control device. This is accomplished by alternately turning upwardly and downwardly the offset forward portion 43 of the station-selector slides, the rear portions of all slides being in the same plane. Each slide is 10 provided with downwardly extending detents 44 which have sloping rear faces 45. The detent latch 46 is carried by the shaft 47 and has a rear portion 48 engaging the sloping surfaces 45 of the detents. The slides 42 are also provided with 15 the upwardly extending clutch bar lugs 49 engaging the clutch bar 50 which is carried on shaft 51. The rear portion 52 of each slide 42 passes through a slot in the rear frame member 12. The clutch bar 50 is held against the rear 20 faces of the lugs 49 by means of the spring 55, the free end of which is secured at 56 to the bracket 38.

The shaft 51 carries a plurality of pawls 58 which are freely rotatable about the shaft. The 25 lower portion of each pawl is provided with a turned up extension 59 which engages the front portion of the upwardly extending clutch bar lug 49. The forward portion 60 of the lower end of each pawl has connected thereto a tension spring 30 61, the other end of which is connected at 62 to an upper extension of the lug 49 of the corresponding key slide 42.

The cam bar 63 is pivotally supported on the shaft 57, the bar extending longitudinally of the 35 assembly. This bar 63 has its upper edge extending against the front face of the row of pawls 58. The upper extension 65 on the cam bar carries the arm 66 which in turn supports the switch cam 67. This switch cam 67 has low portions 68 and 69 and high portions 70 and 71. The cam bar 63 is held in position against the pawls by means of the tension coil spring 72, one end of 40 which is connected to the cam bar and the other end of which is connected to the rear frame 45 number 12.

The switch assembly 73 is supported by bracket 114 from frame member 12 and is provided with nine contact carrying current-conducting spring members which are insulated from each other. 50 The outermost pair 115 and 116 of these contact springs are connected in an automatic frequency control circuit, as best shown in Figure 9 and are in parallel with contacts in another switch assembly 117 operated by the clutch mechanism. 55 The next pair of these conducting spring members 74 and 75 are connected in a circuit such that when their contacts engage each other the grids of audio amplification tubes are short circuited so that the set is silenced. In other words, 60 these two contacting springs serve to open and close the mute control circuit of the set.

The next pair of contacts 77 and 78 are connected in the power circuit of the automatic control actuating motor 79. The free end of spring 75 65 is turned inwardly at 119 to engage an insulating strip 120 held against the face of spring 74. The free end of spring 75 is turned inwardly at 80 to engage an insulating strip 81 held against the face of spring 78. Springs 75 and 116 are 70 normally biased so as to break their contacts with springs 74 and 115, but due to the extensions 80 and 119, an upward or outward movement of spring 75 serves to close the contact between springs 74 and 75 and between springs 115 and 75

116. Due to the insulation 81 and 120, there is no electrical connection between springs 75 and 78 and between 75 and 116, but merely a mechanical connection. Spring 78 has a downturned end 85 adapted to engage the cam rise 70. As shown in Figure 7, spring 78 is normally biased so as to be out of contact with spring 77, so that the motor circuit is normally open.

The innermost three springs 82, 83 and 84 10 comprise the contacts for controlling the direction of rotation of the actuating motor. With the spring 83 in its normal position, as shown in Figure 7, it makes contact with spring 84 and the motor will operate in clockwise direction. When 15 the spring 83 is swung to the left, it breaks contact with spring 84 and makes contact with spring 82, causing the motor to operate in the counterclockwise direction. The upper or free end 86 of the spring 83 extends inwardly to 20 normally be located at an intermediate portion of the low portion 69 of the switch operating cam 67.

The station selector cam discs 31 are each provided with a high cam side 87 and a low cam side 88 as shown in Figure 4. These cam sides are on circular arcs of different radii. The station-locating notch 89 is located at one point of junction between the high and low cam surfaces. The station-locating lug 90 carried by the forward portion of the upper end of the pawl 58 is adapted to fit in the notch 89. The lug 90 and notch 89 are formed on the same taper, so that engagement of the lug in the notch serves to exactly locate the rotary position of the cam disc 31 and of the shaft 23 to which the disc is clamped during automatic tuning operation of the apparatus.

Referring now to Figures 1 and 6, the motor 79 has on its armature shaft 91 the small drive gear 92 which meshes with the gear 93 which is carried on an intermediate stub shaft 94, which also carries the small gear 95. This gear 95 meshes with the large gear 96 on stub shaft 97. This shaft 97 also carries the small gear 98 which 45 meshes with gear 99, which latter gear is mounted upon and drives the main station selector cam shaft 23.

The gear 99 is mounted upon shaft 23 in such manner that frictionally controlled slippage may occur between the gear and shaft. The gear 99 is carried by a hub member 160 which is fixedly secured to the shaft by a set screw. The slotted spring 161 holds the gear 99 on the hub so that the shaft 23 normally moves with the gear 99. The slippage permitted at this point is important in preventing damage to the parts should the gear 99 be driven in any manner while a pawl 58 engages a recess 89 in a cam disc. This slippage also acts in usual automatic operation as a friction brake to ease the shock of sudden stoppage of the motor armature and gear train when the pawl stops rotation of the shaft 23 upon reaching the proper tuning position.

The armature shaft 91 also carries the manual drive pulley 121 which has the rubber friction facing 122. The manual tuning shaft 123 is carried by the bracket 38 and extends at right angles to the main tuning shaft 23 and below the latter shaft, as clearly shown in Figures 1 and 6. The rear end of shaft 123 carries the flywheel 124. The forward end of shaft 123 bears in the fixed sleeve 162 which has its rear end supported by bracket 163 extending from the main bracket 38. The sliding gear sleeve 125 is mounted on

the fixed sleeve 162 and bears directly in the main bracket 38.

The sleeve 125 is slidable relative to the shaft 123 and carries the gear 126 which may be moved into or out of mesh with the crown gear 127. The crown gear 127 is fixed on a rotatable stub shaft 128 to which also is fixed a small gear 129 meshing with the cam disc clamping gear 106. The forward portion of the sleeve 125 is flattened on each side at 130 to facilitate its manual rotation and has the flanges 131 to facilitate manually sliding the sleeve outwardly.

The sliding clutch member 132 is carried upon shaft 123 with which it is caused to rotate by pin 133 fitting in slot 134. This member 132 is 15 provided with the groove 135 to receive the clutch operating fork 136 which is carried by the key bar 50 and moves with that bar. The clutch face 137 is adapted to engage the rubber facing 122 on wheel 121 to manually drive the shaft 23 20 through the same gear train as is used in automatic tuning.

The sleeve 138 is loosely fitted on shaft 123. It is prevented from all but a very short longitudinal movement on shaft 123 by pin 139 fitting 25 in slot 140, which permits a limited rotary movement of the sleeve on the shaft. The spring 141 has one end secured to sleeve 138 and the other end secured to the collar 142, which latter is secured to shaft 123 and rotates therewith. The 30 forward end of the sleeve 138 carries the star wheel 143 fixedly secured thereto. This star wheel 143 is adapted to engage the free end of the unlatching arm 144, which latter is secured to the end portion of the latch plate 46. This arm 35 144 is formed with a downwardly extending portion 145 adapted to coact with the cam end portion 146 of the key bar 50. The lower edge of the forward portion of the bracket 38 has secured thereto the release spring 147 which has a rise 40 40 adapted to be engaged by the gear 126, as that gear is moved into or out of mesh with the crown gear 127. The forward end of shaft 123 has the manual tuning knob 149 secured thereto.

The sleeve 132 carries at its forward end the disc 150, which is formed of insulation and serves to operate the switch assembly 117. This switch is shown in the manual tuning position in Figure 6 and in the automatic tuning position in Figure 8.

The switch 117 is made up of five current-carrying blades, and their connections are indicated on Figure 8. The lower spring 151 is connected to the manual operation pilot light. The next spring 152 is connected to a power supply 55 line of the voltage desired for pilot light operation. The middle spring 153 is connected to the automatic tuning pilot light and the other sides of the two pilot lights are connected to the opposite side of the power line from spring 152. 60 As will be seen from Figures 6 and 8, the spring 152 is normally biased to engage spring 151 to light the manual tuning pilot light. When the sleeve 132 is at the left during automatic tuning, as shown in Figure 8, the disc 150 engages the 65 end 154 of spring 152, lifting it away from spring 151 and into engagement with spring 153 to light the automatic tuning pilot light.

The upper springs 155 and 156 of switch assembly 117 are connected into the automatic 70 frequency control circuit in parallel with the springs 115 and 116 of the key cam switch assembly 73. The end 157 is turned under to engage an insulating spring 158 resting against spring 152. It will be seen that the circuit be- 75

tween springs 155 and 156 will be closed when the clutch assembly is in the position for manual operation and will be open when the clutch is in the automatic position.

5 The automatic frequency control circuit is no part of the present invention and will not be described in detail. It is merely necessary to note that the circuit is such that with the portion of the circuit shown in Figure 8 closed, automatic 10 frequency control does not function. This portion of the circuit is always closed at the clutch switch 117 when the clutch is in position for manual control, and consequently automatic frequency control is not in operation during manual 15 control.

The automatic frequency control circuit springs 115 and 116 on the key cam switch 13 are normally open, as shown in Figure 7, when no key is pushed in. However, as stated above, 20 in this manual control position the automatic frequency control circuit is out of operation due to being closed at switch 117. When a key is pushed in, the cam 67 is swung upwardly and spring end 85 is lifted by cam rise 70 and the 25 automatic frequency circuit is closed between springs 115 and 116 regardless of whether the lug 90 rests on a high or low cam side of its corresponding cam disc 31. Thus, automatic frequency control is kept out of operation even 30 though pushing in the key has opened the circuit between springs 155 and 156. This has been caused by the lug 49 on the key swinging key bar 50 in the clockwise direction, as seen in Figure 7, or in the counterclockwise direction, as 35 seen in Figure 6, which has moved the sliding clutch sleeve 132 to the left by means of fork 136 and lifted switch 117 through insulated disk 150.

However, as soon as the cam disk 31 rotates 40 to the position where the lug 90 fits in notch 89, the bar 63 is swung further to the right as seen in Figure 7, causing the spring end 85 to pass beyond the cam rise 70, whereupon contact is broken between springs 115 and 116; and since 45 it is also at this time broken between springs 155 and 156 of switch 117, automatic frequency control goes into operation to effect the final tuning adjustment. It is important to have the switch formed by springs 115 and 116 in this 50 circuit, as it is not desirable to have automatic frequency control in operation when the motor drive is automatically tuning the set. This is especially true when the station being sought is close to a powerful station which might cause 55 automatic frequency control to operate adversely before the station sought was reached by the motor drive.

In operating the apparatus to manually tune the set, the parts will be in the position shown 60 in Figure 6. All keys are in the outer or released position. Rotation of the manual tuning knob 149 serves to tune the set in the usual manner. The knob 149 rotates the shaft 123 which rotates the clutch slide 132 which has its face 65 137 engaging the face 122 of the pulley 121 on the armature shaft 91. This shaft also carries the first gear 92 of the gear train driving the main shaft 23. Thus turning the manual control knob in either direction causes a corresponding movement 70 of the indicating means and of the radio set tuning device which is rotated by shaft 102. Shaft 102 rotates with shaft 23 due to the coaction of gears 103 and 104.

To put the tuning device in automatic operation, it is merely necessary to select a button

and push it in until it is locked in its inner position. Referring particularly to Figure 7, the slide 42 is locked in this position by the detent latch 46 which is forced downwardly by the sloping rear face 45 of the slide detent 44 and slips upwardly to engage the forward face of the latch 46 as it passes the detent. The latch 46 is swung upwardly by spring 164 shown in Figure 6. As the slide 42 moves rearwardly, it also swings the clutch bar 50 to the left or in the clockwise direction as seen in Figure 7. This is in the counterclockwise direction as seen in Figure 6, and causes the clutch operating fork 136 to move to the left in this figure which serves to separate the clutch faces 137 and 122. 15

Movement of the slide 42 to its locked position also puts a pull upon the spring 61 connected to the slide. The other end of the spring is connected to the forward portion 60 of the lower end of the corresponding pawl 58. This pull therefore swings the pawl 58 in the clockwise direction about shaft 51 as seen in Figure 7. It will be understood that the spring 61 is stronger than spring 72 connected to the cam bar 63 so that bar 63 moves with the upper portion of pawl 58. 20 The pawl 58 moves in the clockwise direction until the lug 90 on the pawl engages the corresponding cam disc 31.

If the lug 90 engages the high side 87 of the disc 31, the switch cam 67 is swung through 30 only a short arc. This lifts spring contact 116, 75 and 78 when the end 85 of spring 78 engages the cam rise 70 and simultaneously shorts the automatic frequency control and the mute control and closes the motor circuit. This movement of cam 67 does not cause it to engage the end 86 of switch spring 83 and the motor direction switch remains in the position of Figure 7. 35

The motor is started and causes the shaft 23 and cam disc 31 to rotate in the clockwise direction as seen in Figure 7. This rotation continues until lug 90 drops into notch 89 in the cam disc. This movement of pawl 58 carries cam bar 63 and the switch cam 67 through a further arcuate movement so that the downturned end 85 of 45 switch spring 78 passes beyond the cam rise 70 and all three switches are opened. The opening of the switches serves to put the automatic frequency control in operation, to open the mute circuit and to open the motor circuit, stopping 50 the motor. The automatic frequency control completes the tuning adjustment of the circuit. 45

The operation is generally similar when the lug 90 engages the low side 88 of the corresponding cam disc 31. The automatic frequency control, mute and motor control switches are all closed in the same manner as when the lug 90 engages the high side 87 of the disc 31. The difference in action is that when the lug 90 engages the low side, the switch cam 67 is swung 55 sufficiently so that the cam rise 71 lifts the end 86 of switch spring 83, breaking contact with spring 84 and engaging spring 82 so that the motor operates in the opposite direction. This moves the disc 31 in the counterclockwise direction until the lug 90 drops in notch 89 when the operation is as before stated. 60

To resume manual tuning, it is only necessary to turn the knob 149 in the usual manner. During the automatic turning, the clutch parts have 70 been brought to the positions shown in Figure 8. The first movement of the knob 149 in either direction rotates shaft 123 and the star wheel 143 engages the end of the unlatching arm 144 forcing it downwardly. This swings the latch 75

bar 46 downwardly, unlatching the key 41 which was last depressed. As the key slide 42 moves forwardly, or to the right as seen in Figure 7, the tension on the spring 61 is released and the 5 pawl 58 is moved in the counterclockwise direction by the cam bar spring 72 which moves that bar in the counterclockwise direction. This draws the lug 90 out of the notch 89 in the cam disc 31 and releases shaft 23 for manual operation. 10 The lug 90 slips easily out of the notch 89 due to the relative slope of their coacting faces and also because there is at this time no rotary thrust by the cam notch faces against the lug.

Also, as the slide 42 moves to the right in Figure 15 7, the clutch bar 50 swings in the counterclockwise direction as seen in Figure 7, or in the clockwise direction as seen in Figures 6 and 8, under the pull of spring 55 and the clutch slide 132 is moved to the right to the position shown 20 in Figure 8. The clutch is thus brought in operation and the further rotation of the knob 149 serves to manually tune the set.

The engagement between the downwardly extending portion 145 of the unlatching arm 144 25 and the cam end portion 146 of the key bar 50 in the unclutched position of Figure 8, has a double function. It maintains the clutch positively in the unclutched position and also positively holds the switch assembly 117 with switch 30 springs 152 and 156 in their upper position.

The importance of the loose connection between sleeve 138 and shaft 123 lies in insuring sufficient movement of the bar 144 when a key is depressed in going from manual to automatic 35 tuning. If the star wheel 143 were rigidly connected to shaft 123 and a key were pushed in with a point on star wheel 143 opposite the upper end of the unlatching bar 144, the movement of the bar would stop at this point so that it could not be unlatched by rotation of shaft 123 and of 40 the star wheel 143.

To change the adjustment of any or all of the 45 cam discs 31, it is first necessary to remove the tuning knob 149. This knob is preferably of any well known type having a friction fit with the flattened end of the shaft 123 so that it is unnecessary to loosen any set screws to remove the knob, which is merely pulled off.

The flanges 131 on sleeve 125 are then grasped 50 and the sleeve pulled forward, or to the left as seen in Figure 8, until the gear 126 meshes with the crown gear 127. During this movement, the gear 126 engages the rise 148 on spring 147 and the lower end of the spring thrusts downwardly 55 the unlatching arm 144 to release any key which may be latched in at the time. The flat sides 130 of the sleeve 125 are then grasped and the sleeve turned in the clockwise direction. Due to the drive between gear 129 and the cam disc 60 clamping gear 106, this rotation of sleeve 125 serves to rotate the shaft 23 and associated disc 31 and clamping cups 32 in the clockwise direction as seen in Figure 7. This rotation continues until the stop lug 26 engages the forward stop 65 27, since no pawl 58 is engaged in a notch 89 due to the automatic release of any key that might have been latched in position.

When the stop lug 26 engages the stop 27, rotation of shaft 123 is stopped. However, the cam 70 cup 39 and the gear 106 are not keyed to shaft 123 and continue to rotate. This rotation continues until the axial end faces of the cams 36 and 40 are in substantial engagement. At this time, the raised portion 112 of spring 109 latches 75 over the lug 108 on the outer face of the gear

106 to yieldingly hold the two opposite cams in this relative position. The cam discs 31 are now no longer positively clamped in position although they are still held frictionally by cups 32 so that they do not turn freely and are not loose on shaft 5 23.

The next step is to press in the button which it is desired to adjust to tune to the selected station. Pressing in this button serves to automatically tune the set to the frequency for which the 10 cam disc 31 associated with the button may happen to be tuned. This will take place properly in spite of the fact that the discs are not at this time rigidly clamped. The lug 90 will now be in the notch 89 of the cam disc 31 to be adjusted, 15 and will hold that disc against rotation. The sleeve 125 is next turned to rotate the shaft 23, and the discs other than the disc held by the lug 90, until the indicator 17 is opposite the desired station frequency or until the desired station is 20 tuned in, if the set is in operation. As many more of the discs may be adjusted as desired merely by pushing the button associated with the disc to be adjusted and tuning in the station by means of sleeve 125.

When the desired adjustments have been made, it is necessary to again rigidly clamp all the discs 31. It is first necessary to release the associated pawl lug 90 from the disc 31 last adjusted. This is accomplished by merely pushing in the sleeve 30 125 until gear 126 engages the rise 148 on the release spring 147 and thus releases the key connected to the pawl. After this, sleeve 125 is drawn forward to engage gear 126 with crown gear 127 and is rotated in the counterclockwise 35 direction. This turns shaft 23 and associated parts in the counterclockwise direction, as seen in Figure 7, until the stop lug 26 engages the rear stop 28. Continued rotation of sleeve 125 rotates gear 106 and cam cup 39 so that the cam faces 40 are rotated relative to cam faces 36 on the cam cup 35 which is keyed to the shaft. As this takes place, the raised portion 112 of spring 109 moves away from lug 108 on gear 106. This movement of sleeve 125 continues until the assembly of discs 31 and cups 32 is firmly clamped 45 together.

The sleeve 125 is now pushed to its inner position and the knob 149 replaced on shaft 123. The apparatus is now in adjustment to be tuned 50 either manually or automatically, as explained above.

It will be apparent that both the setting up of 55 stations on the apparatus and its use are simple and may be readily understood by the user of the set. The station selected by any push-button may be readily changed in a moment without the use of tools and without removing the set panel or working in the rear of the set.

No extra controls are necessary on the front of 60 the set other than the push-buttons themselves. Pushing in any station selector button automatically adjusts the apparatus for tuning by the button if it is not already in the automatic tuning position. A slight rotary movement of the 65 manual tuning knob, as in tuning the set manually, automatically restores the parts to manual tuning position, if they are not already in that position. Consequently, the use of the apparatus involves no especial instructions or operation in 70 changing from one tuning method to the other.

While I have shown certain preferred embodiments of my invention, these are to be understood to be illustrative only as it is capable of change and variation to meet differing conditions 75

and requirements, and I contemplate such changes as come within the spirit and scope of the appended claims.

I claim:

1. In combination with a tuning element of a radio set, a rotating drive shaft having driving connection with said tuning element, a manually rotatable shaft, a driving connection between the manual shaft and drive shaft, said connection including a clutch, a motor operatively connected to the drive shaft, a lever for starting the motor, and means connecting the lever and manual drive clutch whereby said clutch is released upon moving the lever to start the motor.
2. In combination with a tuning element of a radio set, a rotating drive shaft having driving connection with said tuning element, a manually rotatable shaft, a driving connection between the manual shaft and drive shaft, said connection including a spring-held friction clutch, and means whereby rotation of the manual shaft releases the spring and causes the clutch to connect said shaft and the drive shaft.
3. In combination with a tuning element of a radio set, a rotating drive shaft having driving connection with said tuning element, a manually rotatable shaft, a driving connection between the manual shaft and drive shaft, said connection including a clutch, a motor operatively connected to the drive shaft, a lever for starting the motor, means connecting the lever and manual drive clutch whereby said clutch is released upon moving the lever to start the motor, and means whereby rotation of the manual shaft causes the clutch to connect said shaft and the drive shaft.
4. In combination with a tuning element of a radio set, a rotating drive shaft having driving connection with the tuning element, a plurality of cam discs adjustably secured to the drive shaft, each said disc having a high portion and a low portion with a notch therebetween, a locking pawl associated with each cam disc and having a portion adapted to engage the high or low portion and to fit in said notch, a reversible motor for driving said drive shaft, and control switches for said motor operatively associated with said pawls whereby the motor is operated in one direction when a pawl engages the high portion of a disc, is operated in the opposite direction when a pawl engages the low portion of a disc and whereby the motor is stopped when a pawl engages a notch in a disc.
5. In combination with a tuning element of a radio set, a rotating drive shaft having driving connection with the tuning element, a power drive for said drive shaft, a manual drive for said drive shaft, selective stops for said drive shaft, and means whereby rotation of the manual drive releases said selective stops.
6. In combination with a tuning element of a radio set, a rotating drive shaft having driving connection with the tuning element, a power drive for said drive shaft, a manual drive for said drive shaft, selective stops for said drive shaft, keys for actuating said stops, and means whereby rotation of the manual drive releases said selective stops and keys.
7. In combination with a tuning element of a radio set, a rotating drive shaft having driving connection with the tuning element, a power drive for said drive shaft, a manual drive for said drive shaft, keys for putting said power drive in operation and selectively stopping said drive at predetermined points, a clutch connecting the manual drive to the drive shaft, and means whereby actuation of a power drive key releases said clutch.
8. In combination with a tuning element of a radio set, a rotating drive shaft having driving connection with the tuning element, a power drive for said drive shaft, a manual drive for said drive shaft, keys for putting said power drive in operation and selectively stopping said drive at predetermined points, a clutch connecting the manual drive to the drive shaft, means whereby actuation of a power drive key releases said clutch, and means whereby rotation of the manual drive engages said clutch.
9. In combination with a tuning element of a radio set, a rotating drive shaft having driving connection with the tuning element, a power drive for said drive shaft, a manual drive for said drive shaft, keys for putting said power drive in operation and selectively stopping said drive at predetermined points, a clutch connecting the manual drive to the drive shaft, means whereby actuation of a power drive key releases said clutch, means whereby rotation of the manual drive engages said clutch, separate manual drive and power drive pilot lights, switches controlling the circuits to said pilot lights, and means associated with said clutch for actuating said switches.
10. In combination with a tuning element of a radio set, a rotary drive shaft having driving connection with the tuning element, a plurality of adjustable stop means carried by the drive shaft, a manual shaft for rotating the drive shaft, means for collectively clamping and unclamping the stop means to the drive shaft, and a sleeve upon the manual shaft for actuating said clamping means.
11. In combination with a tuning element of a radio set, a rotary drive shaft having driving connection with the tuning element, a plurality of adjustable stop means carried by the drive shaft, a manual shaft for rotating the drive shaft, means for collectively clamping and unclamping the stop means to the drive shaft, and latch means carried by the drive shaft for latching the clamping means in unclamped position.
12. In combination with a tuning element of a radio set, a rotary drive shaft having driving connection with the tuning element, a plurality of adjustable stop means carried by the drive shaft, a manual shaft for rotating the drive shaft, means for collectively clamping and unclamping the stop means to the drive shaft, and a sleeve upon the manual shaft for actuating said clamping means, said sleeve being slidable upon the shaft to move into and out of actuating relationship with the clamping means.
13. In combination with a tuning element of a radio set having an automatic frequency control circuit, a rotating drive shaft having driving connection with the tuning element, a motor drive for said drive shaft, means for selectively starting and stopping the drive motor, switch means operated by said starting and stopping means whereby the automatic frequency control circuit is out of operation when the drive shaft is in motion and in operation when the drive shaft is stopped, a manual drive for the drive shaft, clutch means for connecting the manual drive and the drive shaft, and means whereby the automatic frequency control is put out of operation when the clutch is engaged.
14. In combination with a tuning element of a radio set, a rotating drive shaft having driving connection with the tuning element, supple-

- mental push button controlled tuning mechanism, detent mechanism associated with said push buttons, and mechanical means actuated by rotation of the drive shaft to release said detent mechanism.
15. In combination with a tuning element of a radio set, a manually operable rotating shaft having driving connection with the tuning element, supplemental tuning mechanism comprising push button operated station selecting slides, 5 detents for said slides, and means responsive to manual rotation of the drive shaft to release the detent mechanism.
- 10 16. In combination with a tuning element of a radio set, a manually operable rotating shaft having driving connection with the tuning element, supplemental tuning mechanism comprising push button operated station selecting slides, 5 detents for said slides, detent release mechanism comprising an arm extending adjacent the drive shaft, and a star wheel carried by the drive shaft and adapted to engage the detent release arm upon manual rotation of the shaft to release the 10 detent.

ADOLPH E. GERSCH.
